(21) Appl. No.: **29/129,713**

(57) **CLAIM**

(22) Filed: **Sep. 18, 2000**

The ornamental design for a crown of a round faceted gemstone, as shown and described.

(51) LOC (7) Cl. **11-01**

DESCRIPTION

(52) U.S. Cl. **D11/90**

FIG. 1 is a top plan view of a crown of a round faceted gemstone showing my new design; and,

(58) Field of Search D11/1, 2, 7, 26-29,
D11/35-36, 40-43, 79-92; 63/1.11, 15-15.1,
26-28

FIG. 2 is a side view thereof, all sides are identical/symmetrical. The pavilion is shown in broken lines for illustrative purposes only and forms no part of the claimed design.
